(57) **CLAIM**

We claim the ornamental design for a multi-blade utility saw, as shown and described.

DESCRIPTION

FIG. 1 is a front perspective view of a multi-blade utility saw showing the new design.

FIG. 2 is a right side view of the multi-blade utility saw of FIG. 1.

FIG. 3 is a left side view of the multi-blade utility saw of FIG. 1.

FIG. 4 is a top view of the multi-blade utility saw of FIG. 1.

FIG. 5 is a bottom view of the multi-blade utility saw of FIG. 1.

FIG. 6 is a front view of the multi-blade utility saw of FIG. 1; and,

FIG. 7 is a rear view of the multi-blade utility saw of FIG. 1.

The broken lines depict portions of the multi-blade utility saw in which the design is embodied that form no part of the claimed design.
